DESIGN FOR A BEVERAGE DISPENSER

Robert A. Doyle, Chicago, Ill.

Application October 31, 1941, Serial No. 103,971

Term of patent 14 years

To all whom it may concern:

Be it known that I, Robert A. Doyle, a citizen of the United States of America, residing at Chicago, in the county of Cook and State of Illinois, have invented a new, original, and ornamental Design for a Beverage Dispenser, of which the following is a specification, reference being had to the accompanying drawing, forming a part thereof.

In the drawing:

Fig. 1 is a perspective view of a beverage dispenser, showing my new design; and

Fig. 2 is a perspective view thereof taken in the opposite direction from that of Fig. 1.

I claim:

The ornamental design for a beverage dispenser, as shown.

ROBERT A. DOYLE.
